Patented Mar. 28, 1922.

UNITED STATES PATENT OFFICE.

WILLIAM S. HADAWAY, JR., OF NEW ROCHELLE, NEW YORK.

ELECTRIC FURNACE

1,410,566.

Specification of Letters Patent. Patented Mar. 28, 1922.

Application filed June 17, 1920. Serial No. 389,545.

To all whom it may concern:

Be it known that I, WILLIAM S. HADAWAY, Jr., a citizen of the United States of America, and a resident of New Rochelle, 5 Westchester County, and State, of New York, have invented certain new and useful Improvements in Electric Furnaces, of which the following is a specification, reference being had to the accompanying drawing, forming a part thereof.

This invention relates to improvements in electric furnaces and especially to a new type of apparatus for obtaining high temperatures at low cost. One object of the 15 invention is to provide a simple apparatus for supporting combustion wherein the temperature of admitted vapor is raised above the ignition point of the fuel by electrical energy. Another object is to provide an automatic means for controlling the electrical energy for the heaters. A still further object is to provide means for admitting air to the combustion chamber where it may be combined with the flame and increase the efficiency of the apparatus.

These and other objects of the invention will appear in the following specification in which I will describe the invention, the novel features of which will be set forth 30 in appended claims.

Referring to the drawing:

Figure 1 is a sectional elevation of an apparatus which is made according to and embodies this invention.

Figure 2 is a sectional plan view of the same apparatus the section being taken on the irregular line 2-2 of Fig. 1.

Figure 3 is a diagram of certain electrical circuits which may be used in connection 40 with this apparatus.

Like characters of reference designate corresponding parts in all the figures of the drawing.

10 designates an outer casing of refractory material open at the top, the surface of which may be covered with metal as shown at 11. 20 is an inner casing of similar material also open at the top which fits within the outer casing. A receptacle 30 of refractory material also open at the top fits 45 within this inner casing. It is provided with a flange 31 near its upper end which

fits an annular groove in the inner casing to position the receptacle. 40 is a crucible which has a flange 41 arranged to rest upon 55 an annular shoulder on the inner surface of the inner casing. 42 is the cover of this crucible. A cover 12 of refractory material is arranged to rest upon the top of the two casings and the receptacle and has a dependent boss 13 which projects into the receptacle slightly in order to position the cover and to form a tighter closure.

14 is a vapor intake pipe which extends through the bases of the casings 10 and 20 65 and leads to a chamber formed within the inner casing below the receptacle. A plurality of vapor heaters are placed within this chamber. In this case two are shown designated by the reference numerals 50 and 51. These rest upon ledges formed on the inner surface of the inner casing in such a way as to hold them transversely across the chamber so that they divide the chamber into three compartments 52, 53 and 54. 70 These vapor heaters comprise porous body portions 55 in which are embedded electrical heater elements 56 and 57. A practical form of vapor heater for this purpose is described in detail in patent to me #1,349,131 80 of August 10, 1920.

The lower part of the receptacle is of reduced diameter and through this part extends transversely a hollow dissociation heater or glower 32. This is a perforated 85 tube preferably in the form of a fulgurite and made of oxides of magnesia or other material which may be operated at a glowing temperature and which is a conductor of electricity only when hot. The electrical 90 connections are shown in Fig. 3 in which 60 and 61 are mains from a suitable source of electrical energy. These are connected through a switch 62 with the apparatus. The main 60 is connected by a wire 63 with 95 one end of the heater element 57, the other end of which is connected by a wire 64 with one end of the heater element 56. The other end of the heater element 56 is connected with the other main by a wire 65 100 through stationary contacts 66, 67 and movable contact 68 of an automatic circuit breaker 69 and a wire 70.

A connection is made from an intermediate

ate part of the heater element 57 by a wire 71 with one end of the dissociation heater 32. A wire 72 from the other end of the latter goes to a coil 73 of the circuit breaker, 5 the other end of which is connected with the main 61.

In the outer surface of the inner casing 20 is a spiral groove 21 with the lower end of which is connected an air inlet 22 which 10 may be controlled by a valve 23. An annular groove 24 in the inner surface of the inner casing is connected with the upper part of the spiral groove 21 by radial passages 25. Radial passages 33 through the 15 receptacle connect groove 24 with the space within the receptacle above the material 34 therein which is a combustible such as coke.

The operation of this apparatus is as follows:

20 Low pressure steam is admitted to the inlet 14 to the compartment 52. This steam passes through the vapor heater 50 to the compartment 53 and in doing this its temperature is raised. This heated vapor then 25 passes through the vapor heater 51 into compartment 54 which further raises its temperature. This heated vapor then has access to and passes into the receptacle 30 through the dissociation heater 32. This 30 high temperature escapes into the receptacle through the perforations of the tube 32 and at the same time heats the tube sufficiently to make it a conductor of electricity which heats the tube to a glowing temperature. 35 This temperature of the glowing tube is sufficiently high to dissociate the vapor, breaking it up into its contingent elements hydrogen and oxygen, which are united by combustion and cause the coke 34 to burn to 40 increase the temperature within the receptacle and around the crucible, thus producing an intense heat. The dissociation of the vapor takes up heat and serves as an automatic means for preventing an indefinite 45 increase in the temperature of the tube 32.

When the valve 23 is open, air will be admitted to the receptacle and into the flame which will unite with the burning gases and further increase their temperature. In 50 doing this the air will circulate in the spiral groove 21 where it will become pre-heated to a certain extent and will at the same time increase the heat insulating effect of the casings 10 and 20.

55 While in the structure shown, there are two vapor heaters and a dissociation heater this invention is not restricted to any specific number or arrangements of the units and a single vapor heater may be used or any desired number of them.

When the dissociation heater is energized its temperature rises to a high point and permits a comparatively large current to pass through it. When this current exceeds 60 a predetermined value it will energize the

coil 73 of the automatic circuit breaker and open the latter, thus cutting off the electrical supply from the heater unit 56 and a part of the heater unit 57. A sufficient amount of electrical current will continue to pass 70 through the remainder of the heater unit 57 and the dissociation heater 32 to continue the operation of the device.

The foregoing description is sufficient to show one of the ways in which this invention 75 may be used. The invention itself upon which this application is based is however, broader than the specific embodiment thereof which has been shown and described, and I therefore intend no limitations other than 80 those imposed by the appended claims.

What I claim is:

1. An electric furnace comprising a fuel combustion chamber, an electrical glower therein, and means for passing a vapor 85 through said glower into fuel in the combustion chamber.

2. An electric furnace comprising a fuel combustion chamber, an electrical glower therein, and means for passing a vapor 90 through said glower into fuel in the combustion chamber, said glower being arranged to raise the temperature of the vapor to a point above the ignition point of the fuel.

3. An electric furnace comprising a fuel 95 combustion chamber, an electrical glower therein which is a non-conductor of electricity at ordinary temperatures but a conductor when hot, means for supplying electrical energy to the glower, and means for passing 100 hot vapor through said glower into fuel in the combustion chamber.

4. An electric furnace comprising a fuel combustion chamber, an electrical glower therein which is a non-conductor of electric- 105 ity at ordinary temperatures but a conductor when hot, means for supplying electrical energy to the glower, and means for passing hot vapor through said glower into fuel in the combustion chamber, said glower being 110 initially energized by the combined effect of the electrical energy and the hot vapor.

5. An electric furnace comprising a fuel combustion chamber, an electrical glower therein which is a non-conductor of electric- 115 ity at ordinary temperatures but a conductor when hot, means for supplying electrical energy to the glower, means for passing hot vapor through said glower into fuel in the combustion chamber, said glower being initially energized by the combined effect of the electrical energy and the hot vapor, and means for automatically controlling the electric current passing through the glower.

6. An electric furnace comprising a fuel 125 combustion chamber, a glower tube therein which is a non-conductor of electricity at ordinary temperatures but a conductor when hot, means for supplying hot vapor to the fuel through said tube and means for sup- 130

plying electrical energy to said tube when hot.

7. An electric furnace comprising a fuel combustion chamber, an electrical glower therein, and means for admitting air to the combustion chamber.

8. An electric furnace comprising a fuel combustion chamber, an electrical glower therein which is a non-conductor of electricity at ordinary temperatures but a conductor when hot, means for supplying electrical energy to the glower, and means for admitting air to the combustion chamber.

9. An electric furnace comprising a fuel combustion chamber, an electrical glower therein which is a non-conductor of electricity at ordinary temperatures but a conductor when hot, means for supplying electrical energy to the glower, means for passing hot vapor through said glower into fuel in the combustion chamber, said glower being initially energized by the combined effect of the electrical energy and the hot vapor, and means for admitting air to the combustion chamber.

10. An electric furnace comprising a fuel combustion chamber, a glower tube therein which is a non-conductor of electricity at ordinary temperatures but a conductor when hot, means for supplying hot vapor to the fuel through said tube, and means for admitting air to the combustion chamber.

11. An electric furnace comprising an electric vapor heater, a combustion chamber and a glower in the combustion chamber which is a non-conductor of electricity at ordinary temperatures but a conductor when hot, means for passing a vapor through the vapor heater and the glower into fuel in the combustion chamber.

12. An electric furnace comprising a heat insulating casing constructed to form a chamber, a porous vapor heater dividing the chamber into compartments, a combustion chamber within the casing, a glower in the combustion chamber, and means for passing a vapor through the vapor heater and through the glower into fuel in the combustion chamber.

13. An electric furnace comprising a heat insulating casing constructed to form a chamber, a plurality of porous vapor heaters dividing the chamber into compartments, a combustion chamber within the casing, a glower in the combustion chamber, and means for passing a vapor successively through the vapor heaters and the glower and into fuel in the combustion chamber.

14. An electric furnace comprising a heat insulating casing constructed to form a chamber, a porous partition dividing the chamber into compartments, electric heating elements in said partition, a combustion chamber in the casing, a glower in the combustion chamber, and means for passing a vapor through

the partition and through the glower into fuel in the combustion chamber.

15. An electric furnace comprising a heat insulating casing constructed to form a chamber, a plurality of porous partitions dividing the chamber into compartments, electric heating elements in said partitions, a combustion chamber in the casing, a glower in the combustion chamber, and means for introducing a vapor directly into one of the compartments and through the partitions into the others whereby its temperature is raised in successive stages, and then through the glower into fuel in the combustion chamber.

16. An electric furnace comprising a heat insulating casing constructed to form a chamber, a plurality of porous partitions dividing the chamber into compartments, electric heating elements in said partitions, a combustion chamber in the casing, a glower in the combustion chamber which is a non-conductor of electricity at ordinary temperatures but a conductor when hot, means for introducing a vapor directly into one of the compartments and through the partitions into the others whereby its temperature is raised in successive stages and then through the glower into fuel in the combustion chamber, and a control circuit for the heating elements, said circuit including the glower.

17. An electric furnace comprising a heat insulating casing constructed to form a chamber, a porous vapor heater dividing the chamber into compartments, a combustion chamber within the casing, a glower in the combustion chamber, and means for admitting air to the combustion chamber.

18. An electric furnace comprising a heat insulating casing constructed to form a chamber, a plurality of porous partitions dividing the chamber into compartments, electric heating elements in said partitions, a combustion chamber in the casing, a glower in the combustion chamber which is a non-conductor of electricity at ordinary temperatures but a conductor when hot means for introducing a vapor directly into one of the compartments and through the partitions into the others whereby its temperature is raised in successive stages and then through the glower into fuel in the combustion chamber, and means for admitting air to the combustion chamber.

19. An electric furnace comprising an outer casing and an inner casing, said casings having adjacent surfaces at least one of which is grooved to form a passage, and the inner casing being constructed to form a chamber, a combustion chamber within said chamber, means for heating a vapor and discharging it into the combustion chamber, and means for conducting a vapor from said passage into the combustion chamber.

20. An electric furnace comprising an

outer casing and an inner casing, said casings having adjacent surfaces at least one of which is provided with a spiral groove to form a passage, a combustion chamber within said inner casing, means for heating a vapor and discharging it into the combustion chamber, a vapor inlet connected with

the lower part of said spiral groove, and conduits through the inner casing and through the receptacle connected with the upper part of the spiral groove.

In witness whereof, I have hereunto set my hand this 16 day of June, 1920.

WILLIAM S. HADAWAY, JR.
